UNITED STATES PATENT OFFICE.

RICHARD W. RAFTIS, OF CHICAGO, ILLINOIS, ASSIGNEE TO NATIONAL FIRE PROOFING COMPANY, OF PITTSBURGH, PENNSYLVANIA, A CORPORATION OF PENNSYLVANIA.

BUILDING-BLOCK.

1,080,367.

Specification of Letters Patent.

Patented Dec. 2, 1913.

Application filed April 4, 1913. Serial No. 758,782.

To all whom it may concern:

Be it known that I, RICHARD W. RAFTIS, a citizen of the United States, residing at Chicago, in the county of Cook and State of Illinois, have invented a new and useful Improvement in Building-Blocks, of which the following is a full, clear, and exact description, reference being had to the accompanying drawings, forming part of this specification, in which—

Figure 1 is a plan view showing a portion of a course of blocks embodying my invention, and Fig. 2 is a perspective view of one end of one of the blocks.

My invention has relation to hollow building blocks of clay, terra cotta, etc., and is designed to provide a block having a greater load-bearing capacity, and a greater resistance against shocks, wind pressure, and other strains incidental thereto, than the blocks heretofore used.

My invention also provides a building block which will insure breaks in the mortar joints, there being no continuous mortar joints between adjacent blocks which can act as conductors of moisture or heat.

Referring to the accompanying drawings, the numeral 2 designates the side walls of the blocks and 3 the end walls thereof, these walls being formed on their outer faces with suitable bonding projections and recesses, such as indicated at 4. Each end wall 3 at the central portion thereof is deflected inwardly and thence outwardly, as shown at 3^a, thereby forming a vertical V-shaped recess extending the full dimension of the block. The block has a central web 5 of diamond form, which is connected at two of its angles to the two side walls 2, by means of the short webs 6. The other two angles of the web 5 are connected by short webs 7 with the apices of the inset portions 3^a of the end walls 3. I have shown the webs 6 as being thicker than the web 7 but having air spaces 8 formed therein.

The several webs are symmetrically arranged, forming the four large symmetrical openings 9 through the block and also the central opening 10 and the smaller openings 55 in the web 6. The webs are all of substantially uniform thickness and their thickness is also preferably uniform with the thickness of the side and end walls. The diagonal arrangement of the webs 5 and of the inset portions 3^a, with the connecting

straight webs, establishes a complete bracing for the side and end walls, giving the block a very high load-bearing capacity, as well as greater resistance against shocks, wind pressures, etc. The blocks can be economically manufactured with very much less breakage in shipment and handling than is usual with building blocks of this general type.

It will be noted that the mortar joints 11 between adjacent blocks are not continuous, being entirely broken at the inset portions at the ends of the blocks. This breaking of the mortar joints prevents the direct conduction of moisture through the wall at such joints, as well as the conduction of heat. The V-shaped insets of each two adjacent tiles form the inclosed air spaces 12. It will be noted that these air spaces 12 are of generally similar form and dimensions to the air spaces 10 at the centers of the block, and therefore in successive courses of tiles, with the tiles placed to break joints in such courses, the openings 10 and 12 will register with each other and form substantially continuous air spaces. I do not, however, limit myself to the particular V-form of recesses which I have shown and described, as the shape of these recesses may be changed; and if desired the shape of the openings 10 may also be changed corresponding with the form of said recesses.

What I claim is:

1. A hollow building block having a V-shaped inset in each of its end walls, a diamond web at the center, bracing webs connecting the apices of the insets with the adjacent apices of the diamond web, and short bracing webs connecting the other two apices of the diamond web with the side walls of the block; substantially as described. 95

2. A hollow building block having a V-shaped inset in each of its end walls, a diamond web at the center, bracing webs connecting the apices of the insets with the adjacent apices of the diamond web, and short bracing webs connecting the other two apices of the diamond web with the side walls of the block, the last named bracing webs having air spaces therein; substantially as described. 100

3. A hollow building block having a V-shaped inset in each of its end walls, a diamond web at the center, bracing webs connecting the apices of the insets with the adjacent apices of the diamond web, and 110

2

short bracing webs connecting the other two apices of the diamond web with the side walls of the block, all of said webs being of substantially uniform thickness; substantially as described.

4. A hollow building block having a V-shaped inset in each of its end walls, a diamond web at the center, bracing webs connecting the apices of the insets with the adjacent apices of the diamond web, and short bracing webs connecting the other two apices of the diamond web with the side

walls of the block, all of said webs being of substantially uniform thickness and of substantially the same thickness as the side and end walls of the block; substantially as described.

In testimony whereof, I have hereunto set my hand.

RICHARD W. RAFTIS.
